UNITED STATES PATENT OFFICE.

LOUIS L. CRANE, OF NEW YORK, N. Y.

FLYING-MACHINE.

974,554.

Specification of Letters Patent. Patented Nov. 1, 1910.

Application filed December 10, 1909. Serial No. 532,396.

To all whom it may concern:

Be it known that I, LOUIS L. CRANE, a citizen of the United States, residing at Brooklyn, in the county of Kings, city and State of New York, have invented certain new and useful Improvements in Flying-Machines, of which the following is a clear, full, and exact description.

This invention relates to heavier-than-air flying machines, and the object of the invention is to perfect the construction and increase the stability of such machines as well as to make the steering control of the same efficient.

Broadly considered, the machine of my invention is quite similar to a box-kite, differing therefrom in having one of the sections thereof pivotal while the other section is provided with rudders or steering wings, and with a motor and propeller.

The scope of my invention will be pointed out in the claim.

In the drawings, Figure 1 is a sectional side elevation of my improved machine. Fig. 2 is a plan view, partly broken away, of my improved flying machine. Fig. 3 is a front elevation of my machine. Fig. 4 is a section on line 4—4 Fig. 1. Fig. 5 is a section on line 5—5 Fig. 1.

In carrying out my invention, I provide a box-like frame of tubing having lower longitudinal members 1, and upper horizontal tubular members 2 joined by transverse tubes 3 and 4, respectively, while vertical tubes 9 meet the horizontal and transverse tubes at the corners to form a rectangular box. A transverse brace 10 and a vertical brace 11 may be provided aft of the motor, and I prefer that reinforcing braces 12 and 13 be secured to such vertical tube 11.

The forward tubes of the machine are provided at their center with a rotatable tube 14, on which is secured a box-like frame 15, composed of vertical rods 16 and 17 joining horizontal rods 18 and 19. This tube 14 is journaled in suitable trunnions 20. A crank 21, link 22 and controlling lever 23 pivoted at 24 to the flooring 25 is adapted to control the tilt of the pivoting frame 15. The usual rack 26 and latch 27 are provided to maintain the degree of tilt of the forward pivoting frame or box 15. It will be understood that the box 15 is covered with wind resisting fabric or material.

At a distance aft of the controlling lever 55 the box-like frame is covered with wind resisting fabric 28, and to vertical uprights at the rear there are pivoted rectangular wings or rudders 29 secured on swinging brackets 30 (see detail Fig. 5). The rectangular wings are preferably composed of horizontal members 30^a joined by vertical members 31, and a steering chain or cord 32 is attached to the outer end of each wing. These cords 32 cross each other at the rear 65 of the machine, pass around pulleys 33, and 34, and are connected to a lever 35, preferably controlled by a foot cross bar 36, pivoted at 37, to a bracket mounted on the flooring. A seat 39 for the operator is 70 mounted so that the operator's feet may rest upon the foot cross-bar 36, and his hand be conveniently adjacent to the controlling lever 35. A motor 40 is preferably mounted on the flooring 25, just back of the seat 39. 75 At the center of the vertical tube 11 a bearing 40^a is provided for the shaft of the propeller 41. A gear 42 on the propeller shaft is belted by a belt or chain 43 with the motor gear 44. One forward wheel 45 and two rear 80 wheels 46 are provided, mounted on suitable tubular frames 47, and 48. I prefer that the flooring be open in the form of slats, and I prefer that the covering of the after box be provided with an extending hood 50 as 85 shown in Fig. 1.

In operation the machine is placed on a starting plane, the motor started, and through the action of the propeller blades sent forward at a high speed. The controlling lever 23 is thrown forward to cause the incoming air in the tilting box to raise the machine from the ground. It will be obvious that the elevation can be changed by variously operating this controlling lever 90 to cause different angles of tilt on the tilting box. To swing in a circle the extending rear rudder wings 29 come into play, and are controlled by the operator's feet on the foot cross-bar 36; the draft impinging upon that 100 wing which is caused to lap over the opening, quickly and readily causing the machine to conform its direction of flight at the will of the operator.

In carrying out this invention, details of 105 construction may be varied from those shown, and yet the essence of the invention be retained; some parts might be employed

without others, and new features thereof might be combined with elements old in the art in diverse ways, although the herein described type is regarded as embodying substantial improvements over such modifications.

As many changes could be made in the above construction, and many apparently widely different embodiments of the invention could be made without departing from the scope thereof, it is intended that all matter contained in the above description or shown in the accompanying drawings shall be interpreted in an illustrative and not in a limiting sense. It is furthermore desired to be understood that the language used in the following claim is intended to cover all the generic and specific features of the invention herein described, and all statements of the scope of the invention which as a matter of language might be said to fall therebetween.

I claim as my invention:

The herein described flying machine, comprising a main frame, square in cross sections, vertical and horizontal members therefor, air resisting material on four sides of the main frame extending substantially from the rear to the middle of the frame, a propeller diametrically mounted within the covered portion, a motor and gearing therefor, a frame of less cross sectional area than the main frame, a pivotal mounting therefor in the main frame, air resisting material on four sides of the pivoted frame, the main frame being uncovered between the covered portions, and rudders and steering mechanism substantially as described.

Signed at New York city this 8th day of December 1909.

LOUIS L. CRANE.
